UNITED STATES PATENT OFFICE.

ALBERT HUNDT, OF PANKOW, GERMANY, ASSIGNOR TO GENERAL ELECTRIC COMPANY,
A CORPORATION OF NEW YORK.

TRANSFORMER-TANK BREATHER.

1,100,736.

Specification of Letters Patent. Patented June 23, 1914.

Application filed October 29, 1912. Serial No. 728,446.

To all whom it may concern:

Be it known that I, ALBERT HUNDT, a subject of the King of Prussia, residing at Pankow, Germany, have invented certain new and useful Improvements in Transformer-Tank Breathers, of which the following is a specification.

My invention relates to transformer tanks wherein oil is used as an insulating or cooling medium or both. It is well known that the oil must be kept as dry as possible since the addition thereto of even a small quantity of moisture considerably reduces its electrical insulating qualities, and the insulating qualities of the insulating materials of the transformer proper are likewise liable to suffer.

A transformer case cannot generally be made absolutely air tight because the materials within the tank change appreciably in volume as the load on the transformer increases or decreases; this then requires that there be some connection between the interior of the tank and the atmosphere to allow the equalization of the pressures within and without. Entering air from the surrounding atmosphere tends to convey moisture to the interior of the tank. It has been common therefore to provide a "breather," which generally consists of a vessel open to the interior of the tank and the atmosphere and provided with means, as a hygroscopic material, for removing the moisture from the air within it. The pressures equalize through the "breather," the entering air being deprived of its moisture in the "breather."

One object of my invention is to increase the period of effectiveness of the moisture removing means within the breather by requiring it to act only on air passing between the exterior and the interior of the tank. I propose to do this by providing a valve means, which may assume any one of numerous forms, located in the passage between the moisture removing means and the atmosphere, this valve means closing this passage when the pressures within and without the tank are substantially equal. The moisture removing means is thus kept from contact with the atmosphere and required to act on little air other than that actually passing between the interior and the exterior of the tank.

The accompanying drawings illustrate 55 diagrammatically two constructions involving my invention.

Figure 1 is a sectional elevation of a construction involving my invention wherein the port is normally closed by oil. Fig. 2 60 is also a sectional elevation wherein a double acting valve is provided.

In Fig. 1 the chamber 1 of the breather is shown opening into the interior of the transformer tank 2 which is nearly filled 65 with oil. Upwardly from the bottom of the chamber 1 extends a portion 3 provided through its center with the port to atmosphere. Into the annular portion of the chamber 1 thus formed extends a fixed bell-shaped member 4 as shown. This bell may be held in position by means of the perforated annular ring 5. Above the annular ring 5 is placed the moisture removing means, the vessel 6 containing a hygroscopic 75 material, such for example, as chlorid of potassium. The lower edge of the bell 4 is submerged in oil in the annular bottom of the chamber 1. As the pressure in the interior of the tank rises above or falls below the pressure of the atmosphere, air will be forced out under the edge of the bell 4 and through the passage 3, or will be drawn in through the passage 3 and under the edge of the bell 4. When the pressures within 80 and without the tank equalize, the oil assumes a position somewhat similar to that shown in Fig. 1, thus effectively sealing the interior of the chamber 1 from the atmosphere. Very little air therefore, comes in 85 contact with the moisture removing means of the vessel 6 except that actually passing into or from the tank 2. It is obvious that the length of time the moisture removing means may be allowed to go without attention depends upon the quantity of air it is forced to act upon. By my invention the quantity of air upon which it is required to operate is reduced to a minimum, to but little more than the quantity actually 90 entering and leaving the interior of the transformer tank.

Another construction involving my invention is shown in Fig. 2. In this construction the moisture removing means 6 is likewise 105 located in the chamber 1 above a perforated plate 5. Below this plate is a valve 7 which is capable of moving on the rod 8 both into

and out of the chamber 1. Above and below the valve 7 are springs 9 and 10 respectively. When the pressure within the tank falls below that of the atmosphere, the valve 7 is forced upward against the spring 9 and air from the atmosphere enters the tank through the chamber 1, being deprived of its moisture by the moisture removing means 6. When on the other hand the pressure within the tank exceeds that of the atmosphere, the valve 7 is moved downward against the spring 10, and air passes from the tank. Whenever the pressures equalize, the valve 7 assumes the mid position shown wherein the passageway between the chamber 1 and the atmosphere is closed.

What I claim as new and desire to secure by Letters Patent of the United States, is:

1. The combination with a transformer tank, a device for removing moisture from the air entering the transformer tank, and means for preventing access of the atmosphere to said device on the substantial equali-

zation of the pressures within and without the tank.

2. The combination with a transformer tank, a vessel connected with the interior thereof and provided with a port to the atmosphere, moisture removing means within the vessel and means for closing said port on the substantial equalization of the pressures within and without the tank.

3. The combination with a transformer tank, a vessel connected with the interior thereof and provided with a port to the atmosphere, moisture removing means within the vessel and valve means automatically closing said port on the substantial equalization of the pressures within and without the tank.

In witness whereof, I have hereunto set my hand this 14th day of October, 1912.

ALBERT HUNDT.
